UNITED STATES PATENT OFFICE.

HARRY R. COREY, OF BROOKLYN, NEW YORK, ASSIGNOR TO AMERICAN STOPPER COMPANY, OF BROOKLYN, NEW YORK, A CORPORATION OF NEW JERSEY.

DESIGN FOR A SHEET-METAL TALCUM-BOX.

50,933.

Specification for Design.

Patented June 19, 1917.

Application filed December 30, 1912. Serial No. 739,417. Term of patent 7 years.

To all whom it may concern:

Be it known that I, HARRY R. COREY, a citizen of the United States, residing at No. 519 Fifth street, in the city of Brooklyn, county of Kings, and State of New York, have invented a new, original, and ornamental Design for Sheet-Metal Talcum-Boxes, of which the following is a specification, reference being had to the accompanying drawing, forming a part thereof.

In said drawing, Figure 1 is a perspective view of a sheet metal talcum box showing my new design; Fig. 2 is a plan view of the same.

The design comprises a body which, in cross section, has the form of an elongated rectangle, as distinguished from an oval, and said body is also elongated vertically and has two parallel opposite sides which are nearly square, and two smaller parallel opposite ends which are substantially rec-

tangular and elongated vertically. The vertical corners of this body are rounded by large horizontal curves. The height of the body is rather more than its width, and the body terminates in a top which is rounded upward from a horizontal plane at its extreme edge, and on all four sides, and also from the corners toward the center, where it is surmounted by an upwardly extending cylindrical neck and cap. Just below the edge of said top the body is formed with an outwardly curved semi-cylindrical bead curved around the corners of the body on large curves.

I claim:—

The ornamental design for a sheet metal talcum box, as shown and described.

HARRY R. COREY.
